DESIGN FOR A CORD TASSEL

Aaron A. Radel, New York, N. Y., assignor to Master Venetian Blind Hardware Corporation,
New York, N. Y., a corporation of New York

Application June 22, 1938, Serial No. 77,939

Term of patent 7 years

To all whom it may concern:

Be it known that I, Aaron A. Radel, a citizen of the United States, residing at New York, county and State of New York, have invented a new, original and ornamental Design for a Cord Tassel, of which the following is a specification, reference being had to the accompanying drawing, forming part thereof.

Fig. 1 is a perspective view of the cord tassel showing my new design.

Fig. 2 is a longitudinal central vertical sectional view of the same.

I claim:

The ornamental design for a cord tassel, substantially as shown.

AARON A. RADEL.
